UNITED STATES PATENT OFFICE.

DONNELLY P. FRASER, OF NEW YORK, N. Y.

RADIATOR THERMOMETER-CAP.

1,154,503.

Specification of Letters Patent. Patented Sept. 21, 1915.

Application filed December 9, 1914. Serial No. 876,249.

To all whom it may concern:

Be it known that I, DONNELLY P. FRASER, a citizen of the United States, and a resident of the city of New York, borough of Brooklyn, in the county of Kings and State of New York, have invented a new and Improved Radiator Thermometer-Cap, of which the following is a full, clear, and exact description.

10 This invention relates to automobile equipment and has particular reference to an improved construction of radiator caps.

More definitely stated, the primary object of the invention is to provide a cap for a 15 standard radiator neck, said cap being fitted with a thermometer, an electric lamp to render the readings of the thermometer visible at night or in dark places, and electric terminals operating through or alongside of 20 said cap to energize the lamp.

A further object of the invention is to provide a cap of the character indicated comprising relatively fixed and movable 25 parts or sections, the fixed section being arranged to be fitted as a practically permanent part of the neck while the movable section may be manipulated for the refilling of the radiator, and said fixed and movable cap parts being provided with co-operating 30 electrical connections providing for the movement of the movable section when necessary without special attention to the electrical connections on the part of the operator.

35 Another object of the invention is to provide a thermometer cap, the bulb of which is carried within a pocket in one of the cap parts and thus protected from direct contact with the heated water even though the 40 cap otherwise becomes entirely filled due to the expansion of the water within it.

The foregoing and other objects of the invention will hereinafter be more fully described and claimed and illustrated in the 45 drawings forming a part of this specification in which like characters of reference indicate corresponding parts in all the views, and in which—

Figure 1 is a vertical longitudinal section of the device on the line 1—1 of Fig. 2; Fig. 2 is a rear elevation of the same; and Fig. 3 is a plan view of the rear portion of the relatively fixed cap section.

50 The several parts of this device may be made of any suitable materials, and the rela-

tive sizes and proportions, as well as the general design of the mechanism, may be varied to a considerable extent without departing from the spirit of the invention hereinafter more fully described and specifically claimed.

Referring more particularly to the drawings, I show at 10 the upper portion of a radiator having a neck 11 with an internal screw thread for the attachment of a standard closure cap. In other words, the invention is adapted to be substituted for a standard cap without alteration of the radiator or its neck.

The cap structure comprises two main 70 parts, namely, a relatively stationary part or collar 12 and a movable section 13. The collar 12 has a downwardly projecting exterior flange fitted into the neck 11 and between the shoulder 15 of the collar and the 75 upper end of the neck may be interposed any suitable number or thickness of packing rings or spacers 16 to make a substantially watertight joint and to insure a substantially definite position of the cap with 80 respect to the machine as a whole. The upper end of the collar constitutes a rim 17 having a conical seat with an inclination of substantially 45 degrees to the axis of the cap.

The movable section 13 of the cap is shown herein as hinged at 18 to the rear portion of the collar rim 17. Said section 13 includes a substantially horizontal disk having a periphery 19 with an inclination and 85 form complementary to the seat 17 upon which it seats snugly when in closed position. The under surface of the disk portion of the section 13 is provided with an inverted cup-like projection 20 forming a 90 pocket 21 having an open lower end in communication with the interior of the cap and neck structure.

At 22 I show a thermometer of any suitable nature having a bulb 23 located within 95 the pocket 21 and having its stem fitted snugly in and projecting upwardly through a shank 24 extending upwardly from the disk portion of the section 13.

The upper portion of the section 13 comprises a disk-like indicator casing 25 having a sight opening 26 in its rear face along the center of which the stem of the thermometer extends. The front portion of the indicator casing consists of a hollow cone 27 having 105

the periphery of its base 28 secured in the aforesaid indicator casing rim and in the apex of the cone is secured a lamp 29.

At 30 is arranged a plate of frosted glass 5 between the lamp and the thermometer stem, and on this plate of glass are formed a series of graduations 31 which are plainly visible on the rear face of the glass when the lamp is lighted, but since the glass plate is frosted 10 or ground, the observer is not disturbed by the glare of light from the lamp. The inner face of the cone may be formed as a reflector to intensify the effect of the light, if desired.

15 The wires 32 connected to the lamp extend downwardly through the indicator casing and shank 24 to a pair of terminals 33 located in the rear portion of the disk of the section 20 13 and terminate in cup-shaped insulated members 34 carried permanently by said movable section.

At 35 is formed a housing as a part of the collar 12 into and through which a pair of terminals 36 extend from any suitable 25 direction but shown herein as extending from the outside of the cap and insulated at 37 from the metal of the cap. Conductor wires 38 lead from any suitable source of electricity to the terminals 36. Obviously a 30 switch (not shown) may be located in the circuit of the wires 38 and in reach of the operator for control of the lamp 29. The terminals 36 may be of any suitable form but I prefer to make them curved so as to 35 be located well below the rim 17 of the collar and the upper ends of the terminals are

preferably formed on arcs of circles whose centers coincide with the axis of the hinge 18. It will be appreciated, therefore, that the section 13 of the cap may swing freely 40 around the hinge, the terminals 33 and cups 34 passing freely from or upon the points of the terminals 36 while the section is thus swinging in either direction around its hinge. 45

I claim:

In a thermometer cap for radiators, the combination of relatively fixed and movable sections, the movable section being hinged upon a horizontal pivot adjacent the edge 50 of the fixed section, temperature indicating means carried by the movable section, an electric lamp carried by the movable section to illuminate the temperature indicating means, and coöperating pairs of contacts 55 carried by the fixed and movable sections respectively and insulated therefrom, the contacts carried by the fixed section being curved on arcs of circles concentric with the axis of the hinge aforesaid and projecting 60 into sockets of the movable section whereby the current is completed through the lamp when the cap is closed, substantially as set forth.

In testimony whereof I have signed my 65 name to this specification in the presence of two subscribing witnesses.

DONNELLY P. FRASER.
